UNITED STATES PATENT OFFICE.

PERCY I. ANSORGE, OF BROOKLYN, NEW YORK.

DESIGN FOR A FLOOR LAMP.

Application filed March 21, 1929. Serial No. 30,582. Term of patent 7 years.

To all whom it may concern:

Be it known that I, PERCY I. ANSORGE, a citizen of the United States, residing at 319 St. Johns Place, Brooklyn, in the county of Kings and State of New York, have invented a new, original, and ornamental Design for Floor Lamp, of which the following is a specification, reference being had to the accompanying drawing, forming part thereof.

The figure is a side view of a floor lamp, showing my new design.

I claim:

The ornamental design for a floor lamp, as shown.

PERCY I. ANSORGE.
